(57) **CLAIM**

The ornamental design for a floating shelf, as shown and described.

DESCRIPTION

FIG. 1 is a perspective view of a floating shelf showing my new design;

FIG. 2 is another perspective view thereof;

FIG. 3 is a front elevational view thereof, the rear elevational view is identical;

FIG. 4 is a left side view thereof, the right side view is identical;

FIG. 5 is a top plan view thereof; and,

FIG. 6 is a bottom plan view thereof.

The broken lines in the figures are for the purposes of illustrating portions of the floating shelf, which form no part of the claimed design.
